UNITED STATES PATENT OFFICE

2,552,402

APPARATUS FOR SHARPENING PENCIL
REFILLS

Hans Buser, Zurich, Switzerland

Application March 18, 1947, Serial No. 735,317
In Switzerland December 29, 1944Section 1, Public Law 690, August 8, 1946
Patent expires December 29, 1964

5 Claims. (Cl. 120—91)

1

The present invention relates to an apparatus for sharpening pencil refills having means provided whereby the refill or refill-holder rests by its own weight against the member serving to sharpen the refill. The means consist of a member provided with a friction surface and a sleeve arranged in rotary position which serves to hold the refill-holder, both of which are driven by a driving means in such a way that the friction member and the refill move at a common point of contact in different directions or in the same direction but at different speeds.

Further features of the invention will be apparent from the following description and the drawing setting forth preferred embodiments of the invention.

In the drawings:

Figure 1 is a cross-sectional view of one embodiment of the invention;

Figure 2 is a longitudinal section of the embodiment of Figure 1;

Figure 3 is a cross-sectional view on the line *a—a* of Figure 4;

Figure 4 is a horizontal sectional view of a second constructional embodiment;

Figure 5 is a horizontal sectional view on the line *b—b* of Figure 1, and

Figure 6 illustrates a detail.

In the case of the first constructional embodiment shown in Figures 1 and 2, the pencil-refill rests for sharpening purposes only due to the weight of the refill-holder 5, on the friction-surface of a slanting file 1, which is attached by means of two connecting pieces 2 to a slide 7. The slide 7 can be moved to and fro in the longitudinal direction in the casing 8 (Figure 1) and in the course of this movement carries the file with it. The slide 7 serves as driving means. On the slide 7 there is fastened a rack 3 which engages in a pinion 4 which is rigidly attached to a sleeve 4a. This sleeve 4a is arranged in vertical or approximately vertical position in a holder on the casing 8 and is rotatably mounted therein. The refill-holder 5 of a pencil-refill can be inserted in the sleeve 4a until the tip of the refill rests against the file 1. The refill-holder 5 is secured against twisting in the sleeve 4a by means of a hexagonal holder having three set screws 13 arranged radially in the sleeve (Figures 1 and 5), which are distributed at even distances over the periphery thereof. These screws 13 are set in such a way that the refill-holder can slip down the sleeve by virtue of its own weight until the tip of the refill rests against the file 1. In the pinion 4 of the sleeve 4a there is a hole which

2

serves to limit the depth to which the refill-holder can fall and thus prevents any damaging of the latter.

As the refill-holder may vary considerably in size, which fact may cause difficulty for an exact centering of the pencil-refill inasmuch as the latter can easily break off, a centered bore is provided as clearly shown in Figure 6 in the lower part, i. e. in the pinion part of the sleeve 4a, which bore corresponds to the diameter of the refill. This serves to center the refill and at the same time limit the depth to which the refill-holder 5 can fall.

Due to the arrangement of the friction surface 1 on the opposite side of the refill from the point of pinion engagement with the rack 3, these two parts will move in opposite directions at the common point of contact of the tip of the refill and the friction surface 1, whereby an effective sharpening of the refill is achieved.

The casing 8 is completely closed and under the refill point a container can be provided to hold the graphite dust. This container (which is not shown in the drawing) can be slipped in and out of the casing for emptying the graphite dust.

The mode of operation is apparent from Figures 1 and 2. The refill-holder together with the refill is inserted from above into the sleeve 4a and lowered until the tip of the refill rests against the friction member. The slide 7 is moved back and forth once or twice, which will effect sharpening of the refill. The refill-holder is then taken out of the sleeve 4a together with the sharpened refill.

In the case of the embodiment as in Figures 3 and 4, the friction member consists of a disc 9 in the form of a truncated cone, the jacket of which is designed as a friction surface and against which the tip of the refill of the refill-holder inserted into the sleeve 4a rests. The axis of the friction disc 9 is connected via a pinion 9a to a gear wheel 12 on whose axis a pinion 12a is mounted which meshes with the toothed sector 10a of a pivoted lever 10 having a spring 11 connected thereto. On operating thumb lever 10, the friction disc 9 is turned and, via the pinion and the sleeve 4a, also the refill-holder 5 and the refill. After each movement the thumb lever 10 is returned to its initial position by the tension spring 11. Due to the arrangement of an intermediate gear wheel 12 the sleeve 4a with the refill-holder 5 and the refill on the one hand, and the friction disc 9 on the other hand, are driven in opposite direc-

tions, so that with one or two operations of the thumb lever 10 a sharp refill-tip is obtained.

I claim:

1. Apparatus for sharpening pencil-refills comprising a casing, a substantially vertical hollow sleeve in said casing, said sleeve constituting a holder for a pencil refill, said refill-holder being loosely inserted in said sleeve and a small intermediate space being formed between said refill-holder and said sleeve, a screw inserted in a side of said sleeve and passing therethrough, said screw loosely coacting with said refill-holder to prevent relative rotation between said sleeve and said refill-holder and allow free longitudinal movement of said refill-holder, said sleeve being rotatable, a pinion on the lower end of said sleeve, a slideable rack member in contact with said pinion, drive means for said rack, a friction member comprising a file rigidly connected with said rack for movement therewith, said rack and said friction member being on different sides of the axis of said refill-holder, said refill resting against said file by virtue of its own weight, said file sharpening said refill on movement thereof.

2. Apparatus as claimed in claim 1, characterized in that the rack is so arranged that the file and the refill move at the common point of contact in different directions.

3. Apparatus as claimed in claim 1, characterized in that the driving means consists of a slide which can be moved to and fro in the casing.

4. Apparatus as claimed in claim 1, characterized in that said sleeve serving to hold the refill-holder has at the lower end thereof in the central axis a centered bore, said bore being dimensioned in accordance with the diameter of the pencil-refill, so that said refill is guided by said bore and can be moved in said bore both in rotatory and longitudinal directions.

5. Apparatus for sharpening pencil-refills comprising a casing, a substantially vertical hollow sleeve rotatably journalled in the top of said casing and extending into said casing, said

4
sleeve constituting a pencil refill-holder, said refill-holder being loosely inserted in said sleeve and a small intermediate space being formed between said refill-holder and said sleeve, a screw inserted in a side of said sleeve and passing therethrough, said screw loosely coacting with said refill-holder to prevent relative rotation between said sleeve and said refill-holder and allow free longitudinal movement of said refill-holder, 5 a pinion gear fixed adjacent the lower end of said sleeve, a slide member movably mounted in said casing at substantially right angles to said sleeve, a rack connected to said slide in contact with said pinion gear, a friction member comprising a file attached to said slide and arranged in proximity to the lower end of said sleeve and at an angle thereto, said rack and said friction member being on different sides of the axis of said refill-holder, said refill inserted in said sleeve 10 resting against said friction member under the force of weight of said refill, said slide upon moving rotating said refill in contact with said file thereby sharpening said refill.

HANS BUSER.
